UNITED STATES PATENT OFFICE.

GEORGE J. BUCKEYE, OF KANSAS CITY, MISSOURI, ASSIGNOR, BY DIRECT AND MESNE ASSIGNMENTS, OF ONE-FOURTH TO HOWARD L. MASON, ONE-FOURTH TO SMITH BAKER, AND ONE-FOURTH TO SAMUEL R. HILL, ALL OF KANSAS CITY, MISSOURI, AND ONE-FOURTH TO WILLIAM D. NOWLEN, OF GLEN ROSE, TEXAS.

COMBINATION-LOCK AND CIRCUIT-BREAKER.

1,071,633.

Specification of Letters Patent.

Patented Aug. 26, 1913.

Application filed September 9, 1911, Serial No. 642,545. Renewed January 10, 1913. Serial No. 741,347.

To all whom it may concern:

Be it known that I, GEORGE J. BUCKEYE, a citizen of the United States, residing at Kansas City, in the county of Jackson and State of Missouri, have invented certain new and useful Improvements in Combination-Locks and Circuit-Breakers, of which the following is a specification.

My invention relates to improvements in combination locks and circuit breakers, and my primary object is to provide a device whereby unauthorized persons may be prevented from closing the circuits of automobiles and thus running the same.

In order that the invention may be fully understood, reference will now be made to the accompanying drawing in which:

Figure 1 is a front elevation of the device. Fig. 2 is a rear elevation of the device with a back-plate forming a part thereof removed to show the interior mechanism. Fig. 3 is a horizontal section taken on line III—III of Fig. 2. Fig. 4 shows a group of tumblers employed in carrying out the invention. Fig. 5 is a vertical section taken on line V—V of Fig. 2, and Fig. 6 shows a diagram of a circuit, such as is commonly employed on a gasoline driven car.

In carrying out the invention, I employ a cylindrical casing 1, preferably, struck from a piece of sheet-metal and provided with a removable back-plate 2, upon which the interior mechanism of the device is assembled. After such assembling the back-plate is firmly secured in place by placing it against an annular shoulder 3 of the casing and crimping the margin of the same over said back-plate, as shown, in Figs. 3 and 5. Back-plate 2 is provided with a pair of stud-bolts 4, adapted to extend through the dash-board of an automobile (not shown) and be secured thereto by a pair of nuts 5.

6 designates a knob which is journaled in the front side of the casing and provided with a dial 7, coacting with an "O" on the face of the casing, so that the proper combination for controlling the circuit-breaker may be readily found by a person familiar with said combination. Knob 6 has a notch 8, adjacent the "O" of the dial, so that said "O" can be readily located.

9 designates a screw extending centrally through the back-plate and having its re-

duced threaded portion entering a correspondingly-threaded counterbore in the knob to firmly draw the inner end of the same against a tumbler 10, and bind said tumbler against a sleeve 11, embracing the screw and abutting against the head thereof, so that the knob, the screw, the tumbler 10, and said sleeve will rotate together when the knob is turned. Tumbler 10 has a laterally-projecting stud 12.

13 designates a second tumbler, which is loosely-mounted upon the sleeve 11, and provided with oppositely-projecting studs 14 and 15, the former of which is adapted to coact with stud 12.

16 designates a third tumbler, which like tumbler 13 is loosely-mounted upon the sleeve 11, said third tumbler being provided with a laterally-projecting stud 17 adapted to coact with stud 15 on tumbler 13.

Tumblers 13 and 16 have peripheral notches 18 and 19, respectively, to receive internal teeth on a movable circuit-breaker member 21. Tumbler 10 has a low radius 22 on a level with the bottom of notches 18 and 19, and a high radius 23 on a level with the peripheries of tumblers 13 and 16, for the purpose of controlling the movable member 21 of the circuit-breaker, as will herein-after appear.

Tumblers 10 and 16 are spaced equal distances from tumbler 13, by two washers 24, mounted upon sleeve 11 and provided with internal lugs 25, which enter a peripheral groove 26 in the sleeve, so that the washers will turn therewith.

The movable member 21 of the circuit-breaker comprises three yoke-shaped arms 27 carrying the teeth 20, an arcuate fiber member 28 connected to the ends of arms 27 by pins 29, and a rotary terminal 30 mounted in a longitudinal slot 31, in the face of member 28. The yoke-shaped arms 27 are pivotally-mounted upon a pin 32, secured to the back-plate 2, and the two outer arms are spaced equal distances from the intermediate arm by a pair of washers 33.

The rotary terminal 30 of the circuit-breaker coacts with a resilient terminal 34 fixed to a piece of fiber 35, secured in the casing and having a slot 36 in which said terminal 34 is located. Slot 31 permits member 28 to move vertically without contacting with terminal 34, and slot 36 per-

mits terminal 30 to move vertically without contacting with fiber 35.

37 designates a spring secured in the casing and pressing upon arms 27 to reliably hold the teeth thereof in contact with the tumblers.

Terminal 30 is mounted upon a binding-post 38, from which a circuit wire 39 leads to a magneto 40, and terminal 34 has a binding-post 41 from which a circuit wire 42 leads to a starting-box 43. Magneto 40 and starting-box 43 are of ordinary construction, and connected in circuit in the customary manner.

15 In Fig. 2, of the drawing, the circuit-breaker is shown closed. To open the circuit-breaker and thus interrupt the circuit, it is only necessary to rotate tumbler 10 until its high radius 23 passes beneath teeth 20 and thus raises the movable member 21 until its terminal 30 is out of contact with terminal 34. This operation also raises the teeth 20 to a level with the peripheries of tumblers 13 and 16, so that further turning 25 of tumbler 10 will cause the rotation of tumblers 13 and 16, through the intermediary of studs 12, 14, 15 and 17, until notches 18 and 19 pass out of register with the teeth 20. It will then be impossible to again 30 close the circuit-breaker and complete the circuit until the tumblers are properly manipulated to bring the low radius 22 and the notches 18 and 19 in register with the teeth 20, which can be readily done by any one familiar 35 with the combination. When desired, the combination can be readily changed by loosening screw 9 and turning tumbler 10 to a different point upon said screw.

40 While the device has been shown and described for use in controlling the circuit of an automobile, I of course, do not limit myself to this use, but reserve the right to employ the device wherever it may be used to 45 advantage.

Having thus described my invention, what I claim and desire to secure by Letters Patent, is:

1. In combination, a device consisting of

a casing, a knob journaled in said casing, 50 tumblers within the casing controlled by said knob, and a circuit-breaker controlled by said tumblers, said circuit-breaker embodying a yoke-shaped arm pivotally-mounted in the casing, a member connected to the 55 ends of said arms, a rotary terminal mounted on said member, and a yielding terminal adapted to be engaged by said rotary terminal.

2. In combination, a device consisting of 60 a casing, a knob journaled in said casing, tumblers within the casing controlled by said knob, and a circuit-breaker controlled by said tumblers, comprising a plurality of yoke-shaped arms pivotally-mounted in the 65 casing, a slotted arcuate member connected to the terminals of said arms, a terminal mounted in the slotted portion of said arcuate member, and a resilient terminal adapted to coact with the first-mentioned terminal. 70

3. In combination, a device consisting of a casing having an "O" on the face thereof, a knob mounted in said casing and provided with a dial adapted to coact with the "O" 75 on the face of the casing, tumblers within the casing controlled by said knob, a plurality of said tumblers having peripheral notches, and the remaining tumbler having a low radius on a level with the bottom of 80 said notches, and a high radius on a level with the peripheries of the first-mentioned tumblers, and a circuit-breaker comprising a plurality of yoke-shaped arms pivotally-mounted in the casing and having internal 85 teeth to coact with the tumblers, an arcuate fiber member connecting the ends of said yoke-shaped arms, a rotary terminal mounted on said arcuate fiber member, and a resilient terminal adapted to coact with said 90 rotary terminal.

In testimony whereof I affix my signature, in the presence of two witnesses.

GEORGE J. BUCKEYE.
